UNITED STATES PATENT OFFICE.

BENJAMIN F. WRIGHT, OF HARTWELL, OHIO, ASSIGNOR OF ONE-HALF TO
JAMES P. RAYMOND, OF SAME PLACE.

TARGET-TRAP.

SPECIFICATION forming part of Letters Patent No. 276,124, dated April 17, 1883.

Application filed August 10, 1882. (No model.)

To all whom it may concern:

Be it known that I, BENJAMIN F. WRIGHT, a citizen of the United States, residing at Hartwell, in the county of Hamilton, State of Ohio, have invented certain new and useful Improvements in Target-Traps, of which the following is a specification.

The object of my invention is a trap adapted to throw either a "ball-target" or the "flying target," and when throwing the latter to give it a motion more nearly imitating the flight of a bird. Its object is also to give to the target the spinning motion which causes it to rise and slowly descend without an extraneous lug or clip secured to the target. These objects are attained by the means illustrated in the accompanying drawings, in which—

Figure I is a side elevation of my trap set ready to receive a flying target. Fig. II is a vertical transverse section through line $x-x$ of Fig. I, looking to the front end of the target. This view is enlarged to clearly illustrate the springs which actuate the throwing-arm and the spool around which the springs are coiled. Fig. III is a top plan view of the target-holder. Fig. IV is a perspective view of a flying target intended for use with my trap. Fig. V is a radial section of the view represented in Fig. III, with the guide-arm removed. Fig. VI is a top plan view of the end of the throwing-arm. (Figs. II to VI, inclusive, are drawn to the same scale.) Fig. VII is a top plan view of a modified form of my trap; and Fig. VIII is an end elevation of the same, looking from the rear of Fig. VII.

Similar reference-letters represent like parts wherever they occur throughout the various views.

A represents the base of my trap. It is a hollow shaft terminating in a tripod. The outer ends of the feet are perforated to receive screws by which it is secured to a wooden frame, which is also perforated to receive pins which are driven through these perforations into the ground to secure the trap in place. The hollow shaft A receives a hollow spindle, a, and upon this spindle or shaft is fitted to turn a bracket-arm, B. The bracket is held in place upon the shaft a of base A by a collar, b. A spring, b', secured in bracket B and made to press against the shaft a of base A,

permits the bracket to be turned round upon the shaft, while retaining it with sufficient pressure to prevent its being turned by the jar incident to the action of the throwing-arm. The front end of the bracket-arm B terminates in a hollow spool, b², around which the springs C C' are coiled. The spool b² is notched upon each end to receive the outer bent ends of the springs C C', and has a transverse slot, b³, to receive the end of the throwing-arm D. The throwing-arm is journaled within spool b² upon a bolt, E, which passes through washers and the spool b², the washers being firmly clamped against the ends of the spool to hold the springs in place by a nut, e', upon one end of the bolt. The inner end of spring C is bent around the under edge of arm D, and is compressed by pressing down the arm, as seen in Fig. I, while spring C' is bent over the top of arm D, and, being coiled around the spool in the opposite direction, is slackened by pressing down the arm and compressed by the upward movement, so that arm D is suddenly arrested and sprung backward, causing a jerking motion by which the spinning motion of the target is greatly accelerated. The tension of the springs C C' upon the arm D is regulated by changing their outer hooked ends from one to another of the notches in the end of the spool b², which is done by loosening the screw-nut on bolt E, pushing the washers back, and, after the springs are changed, tightening up the screw to hold them in place. The end of the arm D is turned into an eye or loop and longitudinally notched to receive a notched segment, F, which is journaled upon a pin passing through the looped end of the bar D and through the disk F. Upon top of the bar or arm D is a latch, f, adapted to be turned into any one of the notches in disk F, and hold it in any position desired.

The target-holder G is a flatsheet-metal plate or disk, from the outer edge of which lugs g g' and tongue g' are turned up and over to retain the target, Fig. IV, upon the plate. The holder is mounted upon a rod, f', extending from segment F, which rod passes through lugs g² g³, extending down from the under side of the holder. The lower end of flange g³ is turned out parallel with the face of the holder and notched to engage the edge of disk F. By this means the holder is adjustable around the rod f'. The holder is set at the desired angle

by loosening the screw on the end of the rod f' , when the holder can be slipped back upon the rod, turned to the desired angle, and secured by tightening the screw. The rod f' is bent

5 below a central opening in the holder to provide for using the trap with the ordinary ball-target.

H is a metal bar, and I a flexible strap. These are secured to the holder by screws g^4 , 10 which are tapped into lugs g^5 , extending down from the under side of the holder. The strap has a slot, i , at the end, and the flange of the target, Fig. IV, is notched at 5 to form a hooked tooth, 6, which is passed through the slot in 15 the strap, which is then tightened around the edge of the target by turning the target to its place on the holder G. The strap I is suddenly uncoiled from around the target G by the recoil of the spring C, thus giving the target 20 a spinning motion.

The trigger J is pivoted in the top of the standard, which is shown in vertical section, Fig. I. The arm D is perforated to pass over the top of the shaft a and hooked end of the trigger, and is held in the position shown in Fig. I by a coiled spring, j , until the trap is sprung by pulling upon the cord j' .

The view shown in Fig. I represents the trap as set to throw the target, Fig. IV, and is the 30 position it will occupy ordinarily; but much depends upon the weight of the target used and the direction and velocity of the wind. I have therefore provided a means to adjust the holder on the shaft f' and around the journal-pin of the disk or segment F, so that the skilled sportsman can set the trap to throw the target in any direction desired under any circumstances. My trap (shown in Figs. VII and 35 VIII) throws the target, Fig. IV, as they are 40 usually thrown by traps now in common use—that is, the target begins to rise so soon as it leaves the trap; but this motion does not imitate the flight of a bird. I therefore prefer the form represented in Fig. I, because the 45 target thrown from the trap set in this position gradually descends until it has reached a distance of about twenty yards from the trap, when the spinning motion imparted by the flexible strap I causes it to ascend, giving it 50 the direction of a bird started about that distance from the sportsman.

My trap is changed to throw the common ball-target by adjusting the holder G nearly parallel with the throwing-arm D instead of at 55 a right angle to it, as shown in Fig. I.

Instead of the strap I, for giving the rotary motion to the target, a stud-pin may be secured in the holder G to engage the notch in the flange of the target.

The target shown in Fig. IV is not particularly described herein, because I propose to make it the subject of an independent application.

I do not limit myself to exact form of spring shown to actuate the throwing-arm, as it is evident many well-known forms of springs may be used to impel and suddenly arrest the arm; but I think the form I have shown is the best and simplest.

What is claimed herein is—

1. A target-trap consisting of a fixed standard, A a , a bracket-arm supported by said standard, and a spring-actuated throwing-arm, as D, in combination with a holder consisting of plate G, guide-arm H, and suitable means, 75 such as shown, to secure said holder to the spring-actuated arm, and to retain the target upon the holder during the forward movement of the arm, substantially as herein shown and described.

2. In combination with a target-trap of the character described, the target-holder consisting of plate G, arm H, strap I, lugs g , and tongue g' , said holder being secured to the free end of a spring-actuated arm, as D. 80

3. In a target-trap, the combination, substantially as before set forth, of a bracket, an arm pivoted thereto, a coiled spring, C, exerting its force on the arm when the trap is set, and an oppositely-coiled spring, C', exerting 90 its force on the arm when the latter is at or near its throwing-point.

4. The combination, with the spring-actuated arm D, holder G, segment F, and latch f for adjusting the holder on an axis at right angles 95 to the arm D, of the rod f' and notched flange g^3 for adjusting said holder around an axis parallel to said arm D, substantially as before set forth.

5. In a target-trap of the character described the combination, substantially as specified, of holder G, journaled upon rod f' and having a notched flange, g^3 , with a segment or projection upon said rod to engage the notches of the flange for the purpose of adjusting the 100 holder around the rod.

6. In a target-trap, the combination, substantially as specified, of standard A a , bracket-arm B, and hollow notched spool b^2 , with arm D, bolt E, and springs C C', coiled in opposite 110 directions around said spool and adjustable within the notched ends for the purpose of regulating the pressure of said springs upon arm D.

BENJAMIN F. WRIGHT.
